UNITED STATES PATENT OFFICE.

JOHN KNIERIEM, OF NEW YORK, N. Y., ASSIGNOR TO JONICK-SIRKEN CO., INC., A CORPORATION OF NEW YORK.

DESIGN FOR A CEILING PLATE FOR LIGHTING FIXTURES.

Application filed October 2, 1925. Serial No. 14,993. Term of patent 3½ years.

To all whom it may concern:

Be it known that I, JOHN KNIERIEM, a citizen of the United States, residing in the city of New York, county of New York, and State of New York, and doing business at 138 Livingston St., in said city, have invented a new, original, and ornamental Design for a Ceiling Plate for Lighting Fixtures of which the following is a specification, reference being had to the accompanying drawing, forming part thereof.

Figure 1 is a view in side elevation. Figure 2 is a bottom plan view showing my design, only a portion of the ornamentation being shown complete, it being understood that the remaining portion involves a mere repetition of the part more fully illustrated.

I claim:

The ornamental design for a ceiling plate for lighting fixtures as shown.

JOHN KNIERIEM. [L. S.]
